[57] CLAIM

The ornamental design for a ground sleeve for supporting a pole, as shown and described.

DESCRIPTION

FIG. 1 is a top, front, side perspective view of a ground sleeve for supporting a pole showing our new design;

FIG. 2 is a side view;

FIG. 3 is a top view; and,

FIG. 4 is a bottom view.

The broken line showing of a pole is for illustrative purposes only and forms no part of the claimed design.
